Primary Examiner — T Chase Nelson*Assistant Examiner* — Jonathan J. Han*(74) Attorney, Agent, or Firm* — RatnerPrestia(57) **CLAIM**

The ornamental design for a spoiler for motor vehicle, as shown and described.

DESCRIPTION

FIG. 1 is a front side perspective view of a spoiler for motor vehicle;

FIG. 2 is a rear side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is an elevation view thereof from the right side; and,

FIG. 8 is an elevation view thereof from the left side.

The broken line showing is for the purpose of illustrating portions of the spoiler for motor vehicle that form no part of the claimed design.
